W. W. HOLMES.
SLACK ADJUSTER FOR BRAKES.

No. 577,659.

Patented Feb. 23, 1897.

UNITED STATES PATENT OFFICE.

WILLIAM W. HOLMES, OF CHICAGO, ILLINOIS, ASSIGNOR TO CHARLES F. QUINCY, OF SAME PLACE.

SLACK-ADJUSTER FOR BRAKES.

SPECIFICATION forming part of Letters Patent No. 577,659, dated February 23, 1897.

Application filed December 23, 1896. Serial No. 616,746. (No model.)

To all whom it may concern:

Be it known that I, WILLIAM W. HOLMES, a citizen of the United States, residing at Chicago, in the county of Cook, State of Illinois, have invented certain new and useful Improvements in Slack-Adjusters for Brakes; and I hereby declare the following to be a full, clear, and exact description of the same, reference being had to the accompanying drawings, in which—

Figure 1 is a top plan view of an air-brake cylinder having combined therewith slack-adjuster mechanism embodying my invention, the "take-up-motor" cylinder being partly broken away to show the piston and its spring. Fig. 2 is a longitudinal vertical sectional view of the air-brake cylinder, showing those portions of the slack-adjuster mechanism located within said cylinder, the screw, ratchet-nut, stirrup or fulcrum-guide, and take-up motor being shown in elevation. Fig. 3 is an end view, in elevation, of the air-brake cylinder, showing the relation of the slack-adjuster mechanism to the cylinder-head. Fig. 4 is a detail sectional view of a portion of the air-brake cylinder and its head, showing the cored port leading to the take-up motor of the adjuster mechanism; and Fig. 5 is an elevation of a portion of the head of the air-brake cylinder, showing the opening of the cored port of the air-brake cylinder.

Like symbols refer to like parts wherever they occur.

My invention relates to certain improvements in slack-adjusters for brakes, and is more especially directed to that class of slack-adjusters wherein are combined, with the cylinder-levers of a brake system, a movable fulcrum-block and screw-and-ratchet mechanism for shifting the movable fulcrum to compensate for the wear of the brake-shoes and other slack incident to the brake-rigging.

The several objects I have in view are, first, to protect the slack-adjuster mechanism from exposure to the weather, dust, &c., which tends to shorten the life of the mechanism and at times interferes with its efficiency; second, to reduce the cost of constructing and maintaining the mechanism; third, to obtain a construction wherein the travel of the brake-cylinder piston can be predetermined; fourth,

to render the mechanism more compact and thus save space and avoid the necessity of changing the location of the auxiliary reservoir, (of air-brake systems,) as sometimes becomes necessary with the present slack-adjuster systems, and, finally, to bring the slack-adjuster mechanism more directly under the inspection and supervision of those having charge of the air-brake mechanism. To meet these several requirements and obtain the advantages incident thereto, I introduce within the air-brake cylinder the screw or equivalent means for shifting the movable fulcrum-block of the cylinder-lever, and such a construction or its equivalent embodies the main feature of my invention.

There are other minor features of invention, all as will hereinafter more fully appear.

I will now proceed to describe my invention more fully, so that others skilled in the art to which it appertains may apply the same.

In the drawings, A indicates the air-brake cylinder, B C the cylinder-levers, and D the tie-rod, of the usual or any approved form of an air-brake system.

The lever B is, as usual, pivotally connected to the end of the piston-rod P, while the lever C is pivoted on a movable fulcrum-block F, which travels in a stirrup or fulcrum-guide G, attached to or supported from the cylinder-head a.

The movable fulcrum-block F is caused to travel along the stirrup or guide G by means of a screw-rod S, attached thereto, and which enters the air-brake cylinder A through an opening in the cylinder-head a, which screw-rod carries a ratchet-nut R, having its bearing on the cylinder-head a, and which is rotated by a pawl r, actuated from the take-up motor M.

Within the air-brake cylinder A and attached to the head a where the screw S enters is a screw-case tube s, which extends longitudinally of cylinder A, passes through the piston-head H, and is housed or inclosed by the hollow or tubular piston-rod h. Within the air-brake cylinder A is the usual coiled spring c or equivalent means for causing the return stroke of the piston in taking off the brakes.

Within the walls of the air-brake cylinder

A, at a point just beyond the predetermined or normal travel of the piston-head H, is a cored port p, having its outlet through the head a where it receives the pipe m leading to the take-up motor M.

M indicates the take-up motor, mounted or supported on the stirrup or fulcrum-guide G in juxtaposition to head a of brake-cylinder A. Said motor may be of any desired form, 10 but for the present purposes it has been shown (see Fig. 1) as one having the return stroke of its piston effected by a spring and its piston-rod M' connected by an arm M² with a rod r', arranged in the plane of ratchet-nut R 15 parallel with the piston-rod M' and carrying a gravity-pawl r, which is arranged to actuate the ratchet-nut R on the return stroke of the motor-piston.

The construction being substantially such

20 as hereinbefore set forth, its operation will be as follows: So long as there is no material slack in the brake system or wear of the brake-shoes the piston-head H will have but its normal travel or stroke and the slack-adjuster mechanism will remain quiescent, but so soon as the wear on the brake-shoes (or slack in the system) is sufficient to cause the piston-head H to exceed its "normal" stroke the port p will be uncovered and air from the brake- 25 cylinder A will pass therethrough and by pipe m to the cylinder of the take-up motor M, acting on its piston, and through rod r' cause the idle travel of pawl r over ratchet-nut R. Immediately the pressure in air-brake cylinder 30 35 A is reduced (brakes taken off) the return stroke of piston-head H will unclose port p to the front (or exhaust side) of the piston-head, and take-up motor will then exhaust through pipe m, port p, and the piston-rod opening of 40 air-brake cylinder A. At the same time the spring of the take-up-motor piston will cause the return stroke (or working stroke) of said piston, which carries the rod r' and pawl r with it, causing the rotation of ratchet-nut R, which 45 being itself held against longitudinal motion draws the screw-rod S out of the air-brake cylinder and thus causes fulcrum-block H to move along the guide G away from cylinder-head a sufficient distance to compensate for 50 the lost motion in the system, so that the next stroke of piston-head H will not exceed its normal movement.

The above-noted operation of the devices is repeated as often as the wear of the brake-

shoes or slack in the system becomes sufficient to cause the travel of the piston-head of the air-brake cylinder to exceed its normal travel in applying the brakes. 55

It will be noted that when slack-adjuster mechanism is first applied the screw-rod S is 60 almost entirely housed within the air-brake cylinder, where it is protected from the weather and from dust and dirt, and that thereafter such portions thereof as must be subsequently traversed by the ratchet-nut are 65 at all times protected, so that there is little or no danger of the accumulation of rust or dirt which might reduce the efficiency of or require greater power to operate the adjuster mechanism. 70

Having thus described my invention, what I claim, and desire to secure by Letters Patent, is—

1. The combination with an air-brake cylinder, of a cylinder-lever, a movable fulcrum therefor, a fulcrum-guide supported from the brake-cylinder head, and means for shifting the movable fulcrum, said means housed within the air-brake cylinder; substantially as and for the purposes specified. 75

2. The combination with an air-brake cylinder having a perforate head provided with an inwardly-projecting tube, of a slack-adjuster having a screw-rod and nut-and-ratchet mechanism, said slack-adjuster mounted on 85 the cylinder-head the screw-rod being housed in the tube within the cylinder; substantially as and for the purposes specified. 80

3. The combination with an air-brake cylinder having a perforate cylinder-head and 90 an inwardly-projecting tube, of a piston-head having a hollow stem for the reception of the inwardly-projecting tube of the cylinder-head, a lever-fulcrum movable in a guide or stirrup mounted on the cylinder-head and provided with a screw-rod housed in the tube of the cylinder-head, a ratchet-nut arranged on the screw-rod, and means for rotating the ratchet-nut; substantially as and for the purposes specified. 95 100

In testimony whereof I affix my signature, in presence of two witnesses, this 15th day of December, 1896.

WM. W. HOLMES.
